UNITED STATES PATENT OFFICE.

CHARLES M. LONGYEAR, OF WHITE PLAINS, NEW YORK.

POULTRY-ROOST.

1,129,697.

Specification of Letters Patent. Patented Feb. 23, 1915.

Application filed February 12, 1914. Serial No. 818,837.

To all whom it may concern:

Be it known that I, CHARLES M. LONGYEAR, a citizen of the United States, residing at White Plains, in the county of Westchester and State of New York, have invented certain new and useful Improvements in Poultry-Roosts, of which the following is a specification.

This invention relates to perches, or roosts, and the primary object of the same is the provision of a sanitary roost for poultry.

An object of this invention is the provision of a roost-pole slidably mounted within the building, or the like, and which has means connected to its ends for removing refuse from a fecal receptacle which is mounted directly below the roost-pole, or perch.

With the foregoing and other objects in view, this invention consists in such novel features of construction, combination, and arrangement of parts as will be hereinafter more fully described, illustrated in the accompanying drawings and claimed.

In describing the invention in detail, reference will be had to the accompanying drawings wherein like characters of reference designate like or corresponding parts throughout the several views, and in which,

Figure 1 is a longitudinal sectional view through the improved roost showing the perch in elevation; Fig. 2 is a cross-sectional view, and taken on the line 2—2 of Fig. 1, showing the perch and fecal receptacle in plan; Fig. 3 is an end view showing the exterior of the roost; Fig. 4 is a detail cross-sectional view on the line 4—4 of Fig. 2; and Fig. 5 is a top-plan view similar to Fig. 2, but showing a plurality of perches connected together.

In referring more particularly to the drawings by numerals, 1 and 2 designate the sides of a building which constitutes a chicken roost. The side 2 of the building is provided with a rectangularly-shaped cut-out portion 3 formed therein, which has a metallic plate 4 forming a closure for the same. The upper end of the metallic plate 4 is bent downwardly upon itself and inwardly at right angles thereto, as is clearly shown in Fig. 1 of the drawings. A screw

bolt, or other suitable fastening means 5, is inserted through an aperture formed in the portion of the plate 4 which is bent upon itself and attaches the same to the side 2. The portion 6 of the plate 4 which is bent at right angles to itself engages the end surface of the portion of the side 2, which forms the upper side of the cut-out portion 3. The lower portion of the plate 4 is also bent upon itself, but the bent-up portion does not fit snugly against the plate proper 3, as is clearly shown in Fig. 1 of the drawings. A plate 7 is inserted between the bent portion 8 and the plate 4 proper, being bent at right angles to itself, as at 9, and again bent downwardly, as at 10. The cut-out portion 3 extends downwardly at an angle from the portion 11 of the side 2, and the portion of the plate 7 which extends outwardly from the point 10 engages the angled side 12 of the side 2. This peculiar bending of the plate 7 prevents the plate 4 from being pulled out of the recess 3, and securely attaches the same to the side 2 without the use of bolts, or other similar fastening means.

The plate 4 is provided with a cut-out portion 15 which is centrally located therein and which has a perch, or rod 16 slidably mounted therein. The perch 16 extends laterally across the building and has a handle portion 17 formed upon the end of the same, which projects through the cut-out portion 15. A metallic plate 18 is secured to the inner end of the perch and extends downwardly therefrom forming a hoe for cleaning the fecal receptacle 19 which is disposed directly beneath the perch. The upper surface of the perch is provided with a cut-out portion 20 formed therein, which cut-out portion serves as a receptacle for various types of disinfecting materials. The rod 21 extends longitudinally along the center of the perch 16 and forms a reinforcement for the same.

The fecal receptacle 19 which is disposed directly beneath the perch 16 is formed of any suitable type of sheet metal, and is trough-like in shape, having its upper edges flared outwardly, as at 22. The end of the fecal receptacle 19, which rests upon a projection 23 which is formed on the plate 4,

is open communicating with an opening in the plate 4.

The projection 23 upon which the end of the fecal receptacle rests is a portion of the plate 4 which is cut away to form the opening 24, and is bent inwardly at right angles to the front portion of the plate.

A door 25 is hingedly connected, as at 26, to the plate 4 and forms a closure for the opening 24. A suitable knob 27 is secured to the door to facilitate the opening of the same. The inner end of the fecal receptacle 19 rests upon a bracket 28 which is secured to the side 1 of the poultry roost in any suitable manner.

The lower portion 29 of the metallic plate 18 is of the same width as the interior of the fecal receptacle 19 and forms a means for cleaning the fecal receptacle. When it is desired to remove the refuse from the fecal receptacle 19, the perch 16 and the metal plate 18 are drawn in the direction of the arrow A; and the refuse is forced out of the receptacle through the open end of 25 the same and the opening 24 in the plate 4.

In Fig. 5 of the drawings a modified form of the invention embodying a plurality of perches 16' is shown. The construction of the fecal receptacle and the other features 30 of the invention are identical with the other features shown in the drawing, with the exception of the metallic plate 18 and the handle 17. In Fig. 5 of the drawings a metallic plate 18' which is practically of the same 35 construction as the metallic plate 18 is connected to the inner ends of the two perches 16', while a single handle 17' is connected to their ends which protrude beyond the plate 4'.

40 In practical fields, certain minor features of construction, combination, and arrangement of parts may necessitate alterations to which the patentee is entitled, provided such alterations are comprehended within the 45 scope of what is claimed.

What is claimed is:

1. In a poultry roost, means for supporting poultry, fecal receiving means disposed beneath the poultry supporting means, and 50 means associated with the poultry supporting means and in engagement with the receiving means for supporting the poultry supporting means and for cleaning the receiving means.

55 2. In a poultry roost, means for supporting poultry, means for sliding the poultry supporting means, fecal receiving means disposed beneath the poultry supporting means, and means associated with the poultry 60 supporting means and in sliding engagement with the receiving means for supporting the poultry supporting means and for cleaning the receiving means.

3. In a poultry roost, the combination, of

a slidably mounted perch, a fecal receptacle 65 mounted beneath said perch and means carried by said perch for engagement with said receptacle for supporting said perch and for removing refuse from said fecal receptacle.

70

4. In a poultry roost, the combination of a slidably mounted perch, a fecal receptacle mounted beneath the perch, and a metallic plate for supporting the inner end of said perch, said plate constituting a hoe for engagement 75 with the bottom of said receptacle for cleaning the receptacle.

5. In a device as set forth, a frame, one side of said frame having a cut-out portion formed therein, a plate covering said cut-out 80 portion, a perch slidably mounted in an opening in said plate and extending laterally across said frame, one end of said perch projecting beyond said plate, a handle formed upon the end of said perch which 85 projects beyond said plate, a fecal receptacle disposed directly beneath said perch and means carried by said perch for engagement with said receptacle for supporting said perch and for removing the refuse from said 90 fecal receptacle.

6. In a poultry roost, the combination, of a slidably mounted perch, a fecal receptacle mounted beneath the perch, a metallic plate for supporting the inner end of said perch, 95 said plate conforming in contour substantially to the bottom and sides of said receptacle and constituting a hoe for engagement with said receptacle, and means for operating said perch for cleaning refuse from 100 said receptacle.

7. In a device as set forth, a frame, one side of said frame having a cut-out portion formed therein, a plate covering said cut-out portion, a perch slidably mounted in an 105 opening in said plate and extending laterally across said frame, one end of said perch protruding beyond said plate, a handle formed upon the end of said perch which protrudes beyond said plate, a fecal receptacle disposed directly beneath said perch, 110 a metallic plate secured to the inner end of said perch and extending downwardly therefrom, the lower end of said plate being of the same width as the interior of said fecal 115 receptacle, said plate constituting a hoe for engagement with said receptacle for supporting said perch.

8. In a device as set forth, a frame, one side of said frame having a cut-out portion 120 formed therein, a plate covering said cut-out portion, a perch, slidably mounted in an opening in said plate and extending laterally across said frame, one end of said perch protruding beyond said plate, a handle 125 formed upon the end of said perch which protrudes beyond said plate, a fecal receptacle disposed directly beneath said perch

and means carried by said perch for removing the refuse from said fecal receptacle, said fecal receptacle having one end mounted upon brackets carried by one of the sides of said frame and the other end mounted upon a projection formed integrally with said plate.

In testimony whereof I affix my signature in presence of two witnesses.

CHARLES M. LONGYEAR.
